UNITED STATES PATENT OFFICE.

ROBERT S. BROWN, OF NEW BRITAIN, CONNECTICUT, ASSIGNOR TO THE NEW BRITAIN MACHINE COMPANY, OF NEW BRITAIN, CONNECTICUT, A CORPORATION OF CONNECTICUT.

WHEELED TRUCK.

No. 907,569.

Specification of Letters Patent.

Patented Dec. 22, 1908.

Application filed May 22, 1908. Serial No. 434,222.

To all whom it may concern:

Be it known that I, ROBERT S. BROWN, a citizen of the United States, residing at New Britain, in the county of Hartford and State of Connecticut, have invented certain new and useful Improvements in Wheeled Trucks, of which the following is a specification.

This invention relates to wheeled-trucks. 10 A truck comprising my invention may be employed with advantage in many different connections; for example it may be utilized for supporting tools of various kinds.

I employ the title "wheeled-truck" simply 15 for convenience and also for the fact that the truck is preferably sustained upon wheels by virtue of which said truck can be moved from place to place in a shop or other establishment with ease and facility. Some of 20 the features of the truck may be utilized without the necessity of employing wheels in connection therewith. In like manner certain of the features of the invention may be 25 separately used as it is not necessary that they be joined together in one apparatus.

In the drawings accompanying and forming part of this specification I represent in detail one effective form of embodiment of the invention which to enable those skilled 30 in the art to practice the same will be set forth in detail in the following description while the novelty of the invention will be included in the claims succeeding said description. I wish to make it clear that I do not 35 restrict the invention to the showing thus made for certain variations may be adopted within the scope of my said claims.

Referring to said drawings, Figure 1 is a 40 perspective view of a truck including my invention. Fig. 2 is a top-plan view of a pair of coöperating rockers or oscillatory carriers, the base of the truck being shown in said figure and in section. Fig. 3 is a side elevation of the truck, with portions thereof 45 broken away and in section to more clearly illustrate certain parts and in said figure a portion of the truck-body is broken away from the remainder thereof and with certain adjunctive members is thrown around to 50 more clearly represent the latter. Fig. 4 is a sectional view of parts of the base, trays, crown-piece or top, and a connecting rod, on an enlarged scale. Fig. 5 is a horizontal section of the body. Fig. 6 is a detail view of

the carrier or rocker operating means, a portion of one of the rockers appearing. Fig. 5 is a detail view in section on the line 7—7 of Fig. 6, of latching means, and, Fig. 8 is a sectional detail view hereinafter more particularly described.

Like characters refer to like parts throughout the several figures.

The truck involves in its make-up a base member which may be of any desirable character; for instance it may consist of a shell 65 as 2 which has a foot-flange as 3 at its lower end or bottom of annular form and externally thereof. This flange when the truck is not sustained by its wheels hereinafter described, is adapted to rest on a floor and it 70 provides an ample bearing for the truck; that is the flange provides a means for maintaining the truck solidly and substantially in an upright condition. This base member 2 may be of any suitable material, for example 75 it may be made by casting. The body of the truck in like manner may be of any suitable material, sheet metal answering my purpose. The body illustrated is denoted by 4 and it is of part cylindrical form. To make the body 80 I take a sheet of metal of required area and shape or bend it in some suitable manner to produce the desired object. Preferably the lower edge of the body sets in a circular groove as 5 in the base member 2 while the 85 upper edge thereof fits a similarly shaped groove as 5' formed in the under side of a top or crown-piece as 6. The top or crown-piece and base member 2 are tied together in some suitable manner as by one or more rods or 90 bolts as 7 and by thus tying together such two parts I securely retain in position against lateral and circumferential motion, the part cylindrical body 4 and do not have to employ extraneous fastening means for holding 95 the body in position. There may be any desired number of these rods or bolts as 7, their upper ends being tapped in the underside of the top 6 and their lower ends extending through perforations in an inwardly-extending 100 annular flange as 8 at the upper end of the base 2 and receiving nuts as 9 fitted in downwardly tapered counterbores as 10 in the under side of said flange 8, thereby holding said rods in place and the top and base in 105 assembled relation. I prefer not to rely wholly on the nuts 9 to obtain the function just set forth but will surround the nuts by

a locking means such as a mass of Babbitt metal 11 in each case which is poured into the respective bores 10 to bottom therein and to surround the respective nuts. Such metal when cold prevents the turning of the nuts from the lower ends of the rods 7 and by tapering said bores the Babbitt metal will be retained in place. This construction also insures against the surreptitious removal of the rods should this expedient be adopted to obtain access to the body 4 when the latter is locked closed, all of the rods being as is clear inclosed by the body 4. Said body 4 is also shown as having several trays all of the same general character for which reason each is denoted by 12. The trays 12 are substantially circular and fit comparatively closely within the body 4, each having several holes therethrough for the passage of the tie rods or bolts 7. The trays have a sliding movement on the respective rods to provide for adjustment and they may be held in their respective adjusted positions in any desirable manner, for illustration by means of screws as 13 threaded therethrough and the tips of which are adapted to engage one or more of the rods 7 for the purpose set forth. The top 6 also presents a tray although it is of greater superficial extent than the interior trays 12 and it has flanges as 14 along two ends and a side thereof to prevent the dislodgment therefrom of any tools which may be thereon, the flanges presenting in effect a continuous guard-bead to attain the result in question. The top 6 has no flange along the side thereof in the foreground in Fig. 1, a vise as 15 being attached to this side of the top between the end flanges thereof. This brings the vise in a position approximately centrally between the forward opening of the body, hereinafter referred to, and the solid back of said body so that the downward thrust exerted by a user of the vise is not applied to the top 6 over the said opening but is applied to substantial stock of the body or at a point where the latter is best calculated to resist said thrust. The top 6 can be utilized for supporting various kinds of tools and work while the trays 12 can be used for the same purpose.

The body 4 has an opening or doorway as 16 at the front thereof by which access may be had to the interior of said body 4 for the purpose of putting tools or work on any one of the superposed trays 12 or for removing the same therefrom and this opening or doorway may be closed when desired by a door as 17. When said door is shut it may if necessary be held in such relation under lock and key. The door cross sectionally is of circular form, its width being somewhat greater than that of the opening 16 whereby when closed it can overlap the body 4 adjacent the opening. In the present case said door is supported for swinging movement by

the top 6 and the bottom tray 12 as I will hereinafter describe and in addition to this it has a sliding movement on the flange 8 and against an upwardly-rising guide flange as 18 on the base 2. Complemental to said flange 18 is a flange as 19 depending from the under side of the top 6, both said flanges as will be obvious being of arcuate form.

The door 17 is represented as provided on its inner side with inwardly-extending arms 20 and 21, the lower arm 20 receiving a pivot pin as 22 pending from the bottom tray 12 and the upper arm 21 receiving a substantially similar pivot as 23 pending from the top 6, the two pins being shown as vertically aligned and as extending through the inner ends of said two arms, the latter being rigidly united at their outer ends to the door 17 at or near one edge thereof. In Fig. 1 the door is represented as being open while in Fig. 5 it is shown as closed and when closed it may be held in such relation by a lock, the flanges 18 and 19 to which I have previously referred, preventing the passage of a tool either above or below the door while other means hereinafter described, subserve a like function with respect to the sides of said door.

Upon the outside of the body 4 adjacent to one side of the door-way 16 I fasten in some suitable way as by rivets a strip 24, the length of which equals that of the door 17. This strip therefore extends the complete height of said door-way and is very close to one side wall thereof; it coacts with a substantially similar strip as 25 of the same length fastened to the inside of the door along one of the side edges thereof, both strips being as will be apparent of practically the same length and they are adapted to interlock as shown in Fig. 8 when the door is closed, for which purpose said strips are oppositely curved, the strip 25 when the door is closed fitting in the space between the strip 24 and the body 4. It might be well to state that while the body 4 and door 17 are both circular, the door is upon a greater radius than that of the body so as to provide for a space between the two in which these interlocking strips can be located. Upon the body 4 and in proximity to the door-way at that side thereof opposite that near which the strip 24 is located, is a strip or bead as 26 which on the side thereof next the door 17 is provided with a channel as 27 to receive said door when the same is closed. Upon the outside of said strip 26 is a staple or screw-eye as 28 cooperative with a hasp as 29 on the door and the presence of which provides a means whereby, with the aid of a lock (not shown) the door 17 can be locked closed. In addition to this the hasp 29 acts as a means for easily manipulating the door 17 to either open or close the same. The strips 24 and 26 extending as they do along opposite

sides of and adjacent to the door-way 16 act as reinforcing means for the body 4 and prevent possibility of the same buckling when downward strain is applied thereto while 5 using the vise 15 or while the top 6 is being employed as a work table or bench.

The foregoing is a detailed description of a device which could be used as a stationary tool-cabinet, vise-stand or similar article. I 10 prefer, however, to use in conjunction with said device, wheeled-supporting means whereby the device can be transported without any trouble or effort and I will now describe the means shown for obtaining portability of the apparatus, and such means is of 15 such nature that the truck as a whole can be easily turned or swung around corners.

I have shown as depending from the flange 8 near the forward side thereof bearings or 20 brackets as 30 which receive for oscillation pintles as 31 on the rock-shaft 32. Between the ends of said rock-shaft 32 is a forwardly-extending arm as 33 and near one end thereof is the rearwardly-extending arm 34, the said 25 shaft and the two arms presenting a rocker or carrier for the truck. The arm 33 receives for turning movement near its front end an upright spindle as 35 provided with an axle as 36 for a pair of wheels as 37, such 30 wheels serving as swiveling wheels for the truck.

Near the rear part of the base 2 is a transverse row of bearings all designated by 38 which support a fixed shaft as 39 which constitutes a pivot for a pair of arms as 40, the shaft extending through said arms near the front ends, said ends being joined by a bridge-piece as 41 from which there extends a bent projection as 42, the two arms 40 and the 40 bridge-piece 41 presenting a yoke-like rocker or carrier coöperative with the other carrier to which I have already referred. The projection 42 coöperates with the arm 34 although in the present instance there is not 45 ordinarily a direct engagement between the two. I have shown as tapped through the arm 34 from the under side thereof, a screw as 43 constituting a suitable adjusting device, the upper end of which bears against the forward end of the projection 42 to relatively adjust the two rockers both of which 50 as will be apparent turn about axes between their ends.

The arms 40 carry an axle as 44 which is 55 preferably fixed, and this result can be secured by the aid of a screw as 44' tapped through one of said arms and engaging the axle 44. The latter is provided at its opposite ends with wheels as 45 of larger diameter 60 than the swiveling wheels 37 although this particular relation is not necessary.

The rockers operate against each other between their centers or axes of movement and their wheels are carried outside said centers 65 from which it will be apparent that said

rockers can be so operated as to permit the truck or that part thereof including the base 2 and what is above it being raised from off a floor when it is desired to move the truck from one place to another or to permit said truck to rest solid on the ground or to be supported by said base 2 when the truck should be at rest. In the present instance the raising and lowering of the truck is effected by the application of power to one of the rockers 70 and the rocker thus operated serves to actuate the companion rocker to attain the desired result, and the means shown for this will now be set forth.

Upon the rear side of the body 4 at a suitable height thereof, I fasten in some suitable manner a bracket as 46 and pivot to the same an arm or lever as 47, the latter having a handle as 48 at its free end to facilitate its operation. To the lever or arm 47 near the pivot thereof I prefer to joint a socket-piece as 49 into which is threaded the upper end of a rod as 50 which with the socket piece presents a connecting link that is adjustable as to length, the adjustment being maintained by a check nut as 51 on the rod. Said rod extends through a perforation near the tail of the arm 34 and terminates in an enlargement as 52 which engages against the under side of said arm 34.

In Fig. 6, the lever 47 is shown as occupying the position it assumes when the base 2 is resting upon a floor or like support the several wheels 37 and 45 being at this time out of action although their rims touch such floor 100 or they may be slightly above the same. To put the wheels in action which is done by the elevation of the base 2 the arm 47 is swung to the right in Fig. 6 until it has assumed a position corresponding substantially to that it is shown as occupying in Fig. 3. During the swing of the lever the socket piece 49 and the rod 50 acting as a link will be elevated thereby through the intermediate parts lifting said base 2 from off the floor. As the rod 50 is elevated the arm 34 is lifted thereby the arm 33 being lowered. By reason of the action of said arm 34 through the screw 43, against the projection 42 the latter and hence the forward branches of the arms 40 are elevated while the rear branches of said arms 40 are lowered, whereby both sets of the wheels can be put simultaneously into action. The arm or lever 47 and the coöperating socket-piece 49 and rod 50 act as a toggle so as to reduce to the minimum the power necessary to put said wheels into use, the same being further aided by the length of the said arm 47.

I might use this toggle device as a means for locking the wheels in their operative relations but prefer not to do so as jars or shocks might disturb the same, throwing the toggle off center and permitting the base 2 thereby to descend. To eliminate such a possibility as this I provide means of a positive kind 125 130

to lock the rocker-operating means in the shifted position thereof and that shown for this purpose will now be described.

- Upon the bracket 46 I have shown a pivoted latch 53 normally held in its working relation by a coiled spring as 54 fitted in a socket in said bracket and bearing against the latch. When the arm or lever 47 has completed its shifting movement or that it takes in raising the truck the shouldered portion of the latch is snapped over said arm or lever 47 by the power of the spring 54 to firmly retain said arm or lever in said shifted position. The arm or lever can be easily released to lower the base 2 or the truck of which said base forms a part, by disengaging the shouldered portion of the latch from the arm or lever by power applied to the tail of said latch.
- 20 The members 49 and 50 as is apparent are adjustably connected whereby the time of engagement of the wheels of the truck, with the ground can be regulated independently of the throw of the hand lever 47.
- 25 What I claim is:
1. A truck comprising a top, a base, a body between the top and base, rods inclosed by the body, for connecting the top and base and for holding the body in position therebetween, and a tray supported by said rods.
  2. A truck comprising a top, a base, a body between the top and base, means for tying the top and base together and for also clamping the body therebetween, and a tray in said body.
  3. A truck comprising a tray-like top, a body, a base, means for connecting the top, body and base together, wheeled supporting means, and a tray in said body, the latter having an opening by which access may be had to said tray.
  4. A wheeled truck comprising a top, a body, a base, and rods connecting the top and base, for clamping the body therebetween, the rods having nuts and the base having counterbores to receive said nuts and said base also having filling means in said counterbores for locking the nuts therein.
  5. A truck comprising a body, a base, a top, rods inclosed by the body for clamping the body between said top and base, and trays adjustably supported by the rods, the body having an opening by which access may be had to said trays.
  6. A wheeled truck comprising a top, a base, a body, rods for connecting the top and base and for clamping the body therebetween, the body having an opening by which access may be had to the interior thereof, a door for said opening, and means for interlocking different portions of the door with the body when the door is closed.
  7. A truck comprising a top, a base, a body, rods for connecting the top and base and for clamping the body therebetween, a

tray supported by the rods, the body having an opening by which access may be had to the tray, a door for said opening, and interlocking means connected with the door and body respectively and adapted to interlock when the door is closed. 70

8. A truck comprising a base, a top, a body, means for tying the top and base together and for also holding the body therebetween, a tray in said body, the latter having an opening by which access may be had to the tray, and means for interlockably connecting different portions of the door with the body when said door is closed. 75

9. A truck comprising a base, a top and a body, suitably connected together, the body having an opening by which access may be had to the interior thereof, a door for said opening, and means for interlocking the side edges of the door with the body when said door is closed. 80

10. A truck comprising a base, a top and a body suitably connected together, the body having an opening, a tray in said body, the latter having an opening by which access may be had to said tray, and a door for said opening, the door and body being provided with interlocking devices which coöperate when the door is closed. 90

11. A wheeled truck comprising a base, a top, and a body, rods connecting the top and base and clamping the body there between, the body having an opening by which access may be had to the interior thereof, a door, and devices connected with the door and body and adapted to interlock when the door is closed. 95

12. A wheeled truck comprising a base, a top, a body, rods inclosed by the body, for connecting the top and base and for clamping the body therebetween, the body having an opening by which access may be had to the interior thereof, a tray supported by said rods, and a door for said opening, the door and body having devices which interlock 100 when the door is closed. 105

13. A truck comprising a base, a top, a body, rods connecting the top and base and clamping the body therebetween, a tray supported by the rods, the body having an opening, and strips extending along opposite sides of said opening, on said body one of the strips being grooved to receive the door when closed and the door having a strip to interlock with the other strip on said body also when said door is closed. 115

14. A truck comprising a body, a tray in said body, the latter having an opening by which access may be had to said tray, and wheeled supporting means movable to permit the truck to rest on the ground or to be elevated therefrom, the truck when resting on the ground being substantially immovable. 125

15. A truck comprising a base, a top, a

- body having an opening by which access may be had to the interior thereof, and wheeled rockers supporting the base and movable to raise and lower the base from off the ground the base when on the ground being adapted to rest substantially immovable thereon. 5
16. A truck comprising a top, a base, a body having an opening by which access may be had to the interior thereof, a tray in said body, and wheeled carrying means for said base, operable to permit the base to be raised from off the ground or to rest thereon, the base being shaped to fit substantially flatwise upon the ground when thereon. 10
17. A truck comprising a body having an opening, a tray in said body, and a pair of wheeled rockers for supporting the body the wheels of said rockers being located outside their centers of motion, and means for operating the rockers to cause the truck to be raised or lowered. 20
18. A truck comprising a top, a body, and a base, the body having an opening by which access may be had to the interior thereof, a pair of wheeled rockers for supporting the truck, and toggle means for operating the rockers and by which the base may be lowered onto the ground or raised therefrom. 25
- 30 19. A truck comprising a top, a body, and a base, the body having an opening by which access may be had to the interior thereof, a pair of wheeled rockers connected with the base, and toggle means for operating the rockers and by which the base may be raised from off the ground or lowered thereonto, said toggle means comprising a link consisting of adjustably connected sections. 35
20. A truck comprising a base, and a tray structure above said base, combined with wheeled supporting means for said base, operable to permit the base to rest on the ground or to be elevated therefrom, the base when on the ground being substantially immovable. 40
- 50 21. A truck comprising a body, a top and a base, the body having an opening by which access may be had to the interior thereof and being adapted to inclose tools, and wheeled supporting means for the base operable to permit the base to rest on the ground or to be elevated therefrom the base while on the ground being substantially immovable. 55
22. A truck comprising a body, a base and a top, the body having an opening by which access may be had to the interior thereof, a tray in said body, and wheeled supporting means for the base operable to permit the base to rest on the ground or to be elevated therefrom the base when on the ground being substantially immovable. 60
23. A truck comprising a body, a base and a top, the body having an opening by which access may be had to the interior thereof, a door for said opening, devices which interlock when the door is closed, and wheeled supporting means for the base operable to raise and lower the base from off or onto the ground the base when on the ground being substantially immovable. 65
24. A truck comprising a base and a tray structure above the base for supporting tools, a pair of rockers connected with the base, one of which operates against the other to raise or lower said base from off or onto the ground, and means for operating the other rocker by hand. 70
25. A truck comprising a base and a tool-supporting structure above said base, combined with means having wheels, connected with said base for raising the latter from off the ground or for causing it to move thereonto, the base when on the ground being substantially immovable. 75
26. A truck, combined with wheeled carrying means therefor, toggle means for operating said wheeled carrying means to elevate the truck, and a spring-latch for engaging one of the toggle members to positively hold the truck in an elevated relation. 80
27. A truck, combined with a pair of rockers for supporting the same and having wheels located outside their centers of motion one of the rockers operating against the other between said centers, a lever pivotally mounted and having a handle portion, a link jointed to said lever between the pivot and handle portion thereof, said link being also passed through one of the rockers and having an enlargement at its lower end, and a spring latch for engaging said lever. 85
- In testimony whereof I affix my signature in presence of two witnesses.

ROBERT S. BROWN.
